SELECTIVITY CONTROL

Roy C. Corderman, Chevy Chase, Md.

Application August 3, 1938, Serial No. 222,907

10 Claims. (Cl. 179—171)

This invention relates to radio and allied electrical apparatus, and more particularly to a method and means for effecting a variation in the resonance curve of a tuned circuit, or circuits, in such apparatus whereby selectivity, and consequently the fidelity of program reproduction may be controlled.

In radio reception it frequently occurs that the desired signal is partially blanketed by signals adjacent in frequency which are received with equal or greater strength than the desired signal. If the receiver can be made more selective, the response to the undesired signals is proportionately lessened, and likewise to some degree with extraneous noise. When the desired signal is free from adjacent channel interference it is desirable to dispense with extreme selectivity in order that the modulation sidebands of the signal may be accommodated and the full range of higher audio frequencies occurring in the modulation may be reproduced.

Variable selectivity may be achieved by mechanical methods of changing transformer coupling or by various electrical means such as the use of a positive or a negative feedback, or the use of a tube as a variable impedance across the plate circuit of an amplifier tube. The electrical methods mentioned are subject to control by the action of the automatic volume control system of a receiver and automatic selectivity is accomplished. When a signal is weak and hence is most subject to interference, the automatic volume control bias is reduced in order to effect greater amplification. This reduction of bias is utilized to increase the selectivity of the receiver conjointly with the increase in amplification. In the case of a strong signal, the bias goes more negative, the amplification of the receiver is reduced, and the response curve of the receiver is broadened to permit full range audio reproduction.

It is a primary object of the present invention to provide an improved method of electrically controlling the selectivity of an amplifier stage in radio and related apparatus.

Another object is to provide a system of selectivity control which functions automatically in proportion to received signal strength.

A further object is to provide a system of selectivity control which is less complicated in circuit requirements and which is easier to construct.

Still a further object is to provide a system of selectivity control in which the principal element of control comprises a piezo-electric crystal.

In its present preferred form, the invention is

described and explained as embodied in a receiver of the superheterodyne type, and is utilized in connection with the intermediate frequency amplifier of the receiver. Briefly summarized, the invention contemplates a piezo-electric crystal which is ground to resonate at the intermediate frequency, and which is connected between the cathode and a grid element of the amplifier tube. As the transconductance of the tube is varied by means of grid bias, the selectivity of the input circuit is varied. A low value of negative bias causes maximum selectivity and a progressive reduction of selectivity occurs as the value of negative bias is increased. It will be obvious that any suitable source of bias may be employed and the bias potential may be controlled manually as by a potentiometer, or the grid element or elements to be controlled may be connected to the automatic volume control system of an associated receiver and obtain bias potentials automatically regulated in value from that source.

The accompanying drawing and following description of the invention are intended only for purposes of illustration and the invention is not to be considered as limited to the particular modes of application and function to be later set forth in detail. Additional objects and advantages will in part be presented specifically and in part be obvious when the description is read in connection with the drawing, in which:

Figure 1 is a circuit diagram, partly schematic, of a complete superheterodyne receiver embodying a preferred form of the present invention; and Figures 2 and 3 are alternative modes of connection of the filter circuit schematically presented in Figure 1.

Referring now in more detail to Figure 1, there is shown diagrammatically a complete superheterodyne receiver in which a tunable radio frequency amplifier stage 1 is connected to an antenna 2. A modulator stage 3 receives the output of the radio frequency amplifier 1 and of an oscillator 4, and produces a modulated wave of the desired intermediate frequency in the output circuit 5, which may comprise the primary of a conventional intermediate frequency transformer indicated generally as 6. The secondary winding 7 of the transformer is included in the input circuit of a multi-grid amplifier tube 8, which in this particular embodiment is of the type commercially designated as a 6L7. The intermediate frequency signal is applied between the cathode 9 and signal grid 10 of the tube. A screen grid 11 is provided with a suitable value of positive potential and is situated between the

signal grid 10 and what normally is the injector-grid 12. The balance of the tube elements comprise a suppressor grid 13 which is connected to the cathode 9, and a plate 14 which is furnished with a suitable value of positive, or "B" potential from a source of supply not shown. Bypass condensers 15 and 16 are provided to insure stable operation of the stage. Connected between the grid 12 and cathode 9 of the tube is a piezo-electric crystal 17, which is ground to resonate at the selected intermediate frequency. In the embodiment shown in Figure 1, the grid 12 is maintained at a fixed negative potential with respect to the cathode 9 by means of the drop existing across the cathode bias resistance 18 and the circuit extending from ground through a high impedance 19, which is diagrammatically illustrated as a radio frequency choke. It is possible to substitute a high value of resistance for the choke 19 without adversely affecting the circuit performance.

The output of the tube 8 is passed through another intermediate frequency transformer, indicated generally as 20, and is applied to a second 25 detector and automatic volume control stage 21 of well known design and construction. The audio component of the rectified signal is further amplified by an audio amplifier 22 and is reproduced by a loud speaker 23. The rectified and filtered 30 carrier component of the signal forms the automatic volume control bias, which is a negative potential varying in value with the strength of the received signal. This bias is applied through lead 24 to the signal grid 10 of the amplifier tube 8, and to the signal grid of the tube included in the radio frequency amplifier stage 1.

In the operation of the invention, the maximum 40 selectivity is attained when the bias on signal grid 10 is at the limiting lower value determined by the drop across the cathode bias resistor 18, which is to say, when a weak signal is being received. Stronger signals will produce an automatic volume control bias which is in excess of this lower limit and selectivity will be lessened proportionately. When strong signals are being received 45 as from a local broadcast transmitter or other powerful station, the selectivity is reduced to substantially that of the circuit in the absence of the piezo-electric crystal 17.

In Figure 2 there is shown an alternative form 50 of the variable selectivity circuit illustrated in Figure 1, and like parts therein bear like reference numerals. The form shown in Figure 2 has the negative bias on the signal grid 10 held to the low value determined by the voltage drop occurring 55 across the cathode bias resistor 18, while the bias on the grid 12 is varied to control the selectivity of the stage. The bias may be derived either from the automatic volume control system or from a voltage divider network and applied through a manually controlled potentiometer.

The operation of this form of the invention 60 differs somewhat from that shown in Figure 1 in that the selectivity will remain fairly high up to the middle ranges of bias applied to the grid 12, and the curve will then expand more rapidly as the higher ranges of bias are applied.

A further modification of the invention is illustrated in Figure 3, wherein like parts also bear 70 the same reference numerals as in Figure 1. The grids 10 and 12 in this modification are negatively biased in like degree from the automatic volume control system as shown, or from some other source of variable biasing potential.

75 It appears that in all instances the change of

selectivity with changes of bias values are due to the accompanying changes of tube transconductance under the influence of varying potentials on the grids 10 and 12, either singly as in Figures 1 and 2, or jointly as in Figure 3. In general, high selectivity occurs only when the two grids are held to a relatively low value of bias, and hence the tube transconductance is large. By imposing unequal rates of change of bias on the grids 10 and 12, the slope and rate of expansion 10 of the selectivity curve may be varied, and may even be caused to reverse over a portion of the range.

It will be apparent that the invention herein shown and described may be applied to many uses 15 other than in connection with radio receivers, and may have each variable element individually and manually controlled or automatically controlled. While there have been illustrated what are at present considered to be the preferred 20 embodiments of the invention, many changes and modifications may be made therein by anyone skilled in the art without departing from the spirit and scope of the invention as expressed 25 in the following claims.

What is claimed is:

1. In a wave transmission system, an amplifier stage adapted to operate at a predetermined frequency, an electron tube in said stage, said tube including a cathode, a signal grid element, and a second grid element, a piezo-electric crystal resonant at said predetermined frequency, means connecting said crystal between said cathode and said second grid, means for maintaining a constant biasing potential on one of said grid elements, and means for applying a variable biasing potential to the other of said grid elements in response to variations of signal strength in said system, whereby the selectivity of said amplifier stage may be varied. 40

2. In a radio receiver having an automatic volume control system, an amplifier stage adapted to operate at a predetermined frequency, an electron tube in said stage, said tube having a cathode, a signal grid element, and a second grid element, a piezo-electric crystal resonant at said predetermined frequency, means connecting said crystal between said cathode and said second grid, and means acting in response to said automatic volume control for varying the transconductance of said tube, whereby the overall selectivity of said receiver may be varied. 50

3. In a radio receiver having an automatic volume control system, an amplifier stage adapted to operate at a predetermined frequency, an electron tube in said stage, said tube having a cathode, a signal grid element, and a second grid element, a piezo-electric crystal resonant at said predetermined frequency, means connecting said crystal between said cathode and said second grid, and a connection between one of said grids and said automatic volume control system, whereby the overall selectivity of said receiver may be varied in response to variations in received signal strength. 60

4. In a radio receiver having an automatic volume control system, an amplifier stage adapted to operate at a predetermined frequency, an electron tube in said stage, said tube having a cathode, a signal grid element, and a second grid element, a piezo-electric crystal resonant at said predetermined frequency, means connecting said crystal between said cathode and said second grid, and a connection between said signal grid and said automatic volume control system, 70

whereby the overall selectivity of said receiver may be varied in response to variations in received signal strength.

5. In a radio receiver having an automatic volume control system, an amplifier stage adapted to operate at a predetermined frequency, an electron tube in said stage, said tube having a cathode, a signal grid element, and a second grid element, a piezo-electric crystal resonant at 5 said predetermined frequency, means connecting said crystal between said cathode and said second grid, and a connection between both of said grids and said automatic volume control system, whereby the overall selectivity of said receiver 10 may be varied in response to variations in received signal strength.

6. In a wave transmission system, an amplifier stage adapted to operate at a predetermined frequency, an electron tube in said stage, said tube 20 including a cathode, a signal grid element, and a second grid element, a piezo-electric crystal resonant at said predetermined frequency, a connection between said crystal and said cathode, a second connection comprising a continuous conductive path between said crystal and said second grid, and means for varying the transconductance of said tube, whereby the selectivity of 25 said amplifier stage may be varied.

7. In a wave transmission system, an amplifier stage adapted to operate at a predetermined frequency, an electron tube in said stage, said tube 30 including a cathode, a signal grid element, and a second grid element, a piezo-electric crystal resonant at said predetermined frequency, a connection between said crystal and said cathode, a second connection comprising a continuous 35 conductive path between said crystal and said second grid, and means for varying the transconductance of said tube in response to variations of signal strength in said system, whereby the selectivity of said amplifier stage may be varied.

8. In a wave transmission system, an amplifier

stage adapted to operate at a predetermined frequency, an electron tube in said stage, said tube including a cathode, a signal grid element, and a second grid element, a piezo-electric crystal resonant at said predetermined frequency, a 5 connection between said crystal and said cathode, a second connection comprising a continuous conductive path between said crystal and said second grid, and means for applying a variable biasing potential to one of said grid elements, 10 whereby the selectivity of said amplifier stage may be varied.

9. In a wave transmission system, an amplifier stage adapted to operate at a predetermined frequency, an electron tube in said stage, said tube 15 including a cathode, a signal grid element, and a second grid element, a piezo-electric crystal resonant at said predetermined frequency, a connection between said crystal and said cathode, a second connection comprising a continuous 20 conductive path between said crystal and said second grid, impedance means effectively in shunt with said crystal, and means for applying a variable biasing potential to one of said grid elements, 25 whereby the selectivity of said amplifier stage may be varied.

10. In a wave transmission system, an amplifier stage adapted to operate at a predetermined frequency, an electron tube in said stage, said 30 tube including a cathode, a signal grid element, and a second grid element, a piezo-electric crystal resonant at said predetermined frequency, a connection between said crystal and said cathode, a second connection comprising a continuous 35 conductive path between said crystal and said second grid, means for maintaining a constant biasing potential on one of said grid elements, and means for applying a variable biasing potential to the other of said grid elements, whereby the selectivity of said amplifier stage may be 40 varied.
